TIE PLATE ARRANGEMENT FOR RAILROADS

Theodore W. Stedman, New York, N. Y.

Application February 3, 1939, Serial No. 254,374

3 Claims. (Cl. 238—283)

My invention relates to tie plate arrangements adapted for railroad use.

My invention has particular reference to a tie plate arrangement wherein lateral movement of the railroad rail is prevented by a novel construction embodying a clip member which forms a detachable part of said tie plate arrangement.

My invention has further reference to novel arrangements for decreasing side sway or "nosing" of the railroad traffic.

My invention has further reference to a tie plate arrangement wherein the resilient or rubber structure thereof is built-up or laminated in a novel manner.

My invention resides in the tie plate arrangements, features and improvements of the character hereinafter described and claimed.

For an understanding of my invention and for an illustration of some of the forms thereof, reference is to be had to the accompanying drawings, in which:

Figure 1 is a plan view of the tie plate arrangement of my invention;

Fig. 2 is a vertical sectional view of the arrangement shown in Fig. 1;

Fig. 2a is a vertical sectional view showing a modification of the invention;

Fig. 3 is an enlarged, vertical sectional view showing a part of the novel shoe of my tie plate arrangement;

Fig. 3a is a fragmentary, vertical sectional view illustrating a feature of the invention;

Fig. 4 is a plan view of the aforesaid shoe;

Fig. 5 is a plan view of the novel harness jacket of my invention; and

Fig. 6 is a vertical sectional view showing a modification of the invention.

Referring particularly to Figs. 4 and 5, H represents a lock clip harness jacket and S represents a shoe, these structures being utilizable in accordance with my invention as hereinafter described.

In the form of the invention herein illustrated, the harness jacket H is a plane piece of steel, or equivalent, having suitable thickness and preferably of generally rectangular configuration. Adjacent its periphery and on each side thereof, the aforesaid harness jacket comprises a plurality of spaced vertical passages a through which are adapted to extend the respective fastening members or screw spikes which extend downwardly into the cross tie, or equivalent. Inwardly of the passages a, the harness jacket H is provided with an opening or passage a2 of square, rectangular or other suitable configuration, this passage a2

being bounded on one pair of opposite sides thereof by the respective harness jacket sections through which the passages a extend and said passage a2 being bounded on the other pair of opposite sides thereof by the respective harness jacket rib sections a3, a3. In accordance with the invention, the harness jacket H, along opposite sides thereof, is provided with the respective passages a4 which, preferably and as indicated, merge or open into the aforesaid passage a2.

The aforesaid shoe S comprises a sole plate or base b and a cushion section b1 upstanding therefrom. The sole b comprises a plurality of vertical passages b2 through which downwardly extend the aforesaid respective fastening members or screw spikes as hereinafter more fully described. The cushion section b1, on its periphery, comprises a lower inclined section b3 from which extends the upper vertical wall surface b4. Extending transversely across the cushion section b1 is or are one or more grooves b5 having the characteristics hereinafter described in detail.

Referring particularly to Figs. 1 and 2, 1 represents a wooden railroad cross tie or equivalent, and 2 represents one of the steel rails of a railroad track. Adjacent each end of each of the cross ties 1 is disposed one of the above described shoes S, the bottom surface of the shoe resting flatwise upon the upper cross tie surface. A harness jacket H is associated with each of the aforesaid shoes S, said harness jacket H resting upon and conforming generally with those respective sections of the supporting shoe S which are outwardly of the cushion section b1 thereof, said cushion section b1 extending upwardly through the aforesaid passage a2 of the harness jacket H and the upper surface of said cushion section b1 being disposed above the upper surface of said harness jacket H, Fig. 2, so that the rail 2 may rest thereon.

It will be understood that the shoe S and the harness jacket H are of such character that, when they are associated together as above described, the passages b2 of the sole b will be aligned with the respective passages a of the harness jacket H. Accordingly, it follows that the screw spikes 3, or equivalent, may be passed downwardly through the respective sets of aligned passages a, b2 so as to secure the tie plate assembly to the cross tie, Fig. 2. In this connection, the aforesaid inclined section b3 serves as a guide to properly center and maintain the cushion section b1 within the passage a2 of the harness jacket H as shown in Fig. 1 so that there is a

space between the vertical surface of the cushion section and the adjacent vertical surface of the harness jacket.

In accordance with the invention, lateral movement of any rail 2 in either direction is prevented by a novel arrangement which, as herein shown, comprises a pair of lock clips 4 forming part of each tie plate assembly, these lock clips being disposed on opposite respective sides of the rail 2, Figs. 1 and 2.

Each lock clip 4 comprises a base section 4a, a depending locking section 4b and an upper clamping section 4c. As clearly shown in Fig. 2, the lock clip base section 4a is of plane configuration and engages flatwise against the upper surface of the harness jacket H, said base section 4a comprising a passage 4d adapted to be aligned with the adjacent set of aligned passages a, b2. The lock clip locking section 4b is received by the adjacent passage a4 of the harness jacket H, and the lock clip clamping section 4c forms the upper part of a pocket in which the base of the rail 2 is received.

The hereinbefore described shoe S may be and preferably is formed from suitable resilient material, such as natural rubber, synthetic rubber or equivalent, a pad of substantially non-absorbent fibrous or fabric material enveloped by some agent such as rubber, latex or the like, etc. When the shoe S is formed from such resilient material, it is desirable, although not necessary, that each set of aligned passages 4d, a be lined with a sleeve 5 which, preferably, comprises an integral upper flanged section 5a, this sleeve 5 and its flanged section 5a preferably being formed from resilient material as above noted and said sleeve 5 being reinforced if desired, although not necessarily.

With an assembly of the character described above and as illustrated in Fig. 2, it will be understood that the diameter of each set of aligned passages 4d, a is substantially larger than the diameter of the adjacent passage b2 of the shoe S. Accordingly, the sleeve 5 seats properly within said aligned passages 4d, a. Further, the passage defined by the interior of said sleeve 5 and the adjacent passage b2 of the shoe S are of the proper diameter to more or less snugly receive the shank of the associated screw spike 3.

From the foregoing, it clearly appears that each tie plate assembly comprises a shoe S and an associated harness jacket H. The sole b of the shoe S rests upon the cross tie and the base of the rail rests upon the cushion section b1 of said shoe S. Two screw spikes 3, or equivalent, on each side of the rail 2 secure the assembly to the cross tie and, on each side of said rail 2, one screw spike 3 extends downwardly through the passage 4d of the adjacent lock clip 4, the passage a of the harness jacket and the aligned passage b2 of the shoe S so as to thereby secure said lock clip 4 in position to prevent lateral or side movement of the rail 2. The other screw spike 3 on each side of the rail 2 is not associated with a lock clip 4 and, therefore, said last named screw spike extends downwardly through the adjacent passage a of the harness jacket and the aligned passage b2 of the shoe S. When the tie plate arrangement embodies the described sleeves 5, it will be understood that these sleeves will have different heights, respectively, as well shown at the left and right of Fig. 2.

The advantages of an arrangement of the character described are numerous and of importance. In the first place, the use of the rubber

shoe in combination with the harness jacket cushions the shock of traffic, lengthens the life of the road bed and rolling stock, decreases expense items, etc., etc., all as described in detail in U. S. Letters Patent No. 2,110,894. In the second place, the lock clips 4 serve the particularly useful purpose of enabling the harness jackets H to be plane, flat sheets of steel—no special rolls are required for the production thereof. These harness jackets may be plane as specified because the lock clips serve as the shoulders against which the base of the rail abuts. Further, the lock clips serve the useful purpose of eliminating the regular gauge spikes which would otherwise be required.

From another view point, the use of the assembly comprising the spike 3 and lock clip 4 serves three purposes, namely, (1) as the anchor spike, (2) as the gauge spike, and (3) as the shoulder against which the base of the rail abuts. This is a great simplification as regards prior art practice.

The use of the sleeves 5 is desirable particularly in those installations where the locomotive operation is effected by electrical power. As clearly appears from Fig. 2, the rail 2 is completely insulated, in an electrical sense, from the cross tie, or equivalent. This condition would not exist if the sleeves 5 were omitted. It shall be understood, however, that my invention is not to be limited to the use of these sleeves 5.

The hereinbefore described groove b5 is known as a "graduated deflection groove" and forms an important feature of my present invention. The depth of this groove in the cushion section b1 gradually decreases in a direction from left to right, Fig. 2, the greatest depth of the groove being on the inside of the rail. This groove tends to and does automatically control gauge irregularities of the track and, in so doing, restrains the rolling stock from side sway. In case the gauge is somewhat wide, the groove b5 tends to contract the same during passage of the rolling stock. In case the gauge is somewhat narrow, said groove b5 tends to expand the same as the rolling stock passes thereover. In other words, the deflection groove b5 has the desirable quality of tending to confine the track at all times against the wheel flanges.

Referring to Fig. 2, the top surface of the cushion section b1 is shown as canted so that the rail tilts inward toward the center of the track. The degree of this cant may be such as is suitable, for example, 1:20, 1:40, 1:60, etc. While the cant arrangement of Fig. 2 is properly operative, a more preferable arrangement, when using a non-canted harness jacket H of uniform thickness as shown in said Fig. 2, involves a sole plate b as illustrated in Fig. 2a wherein that side of the sole plate b shown at the right is of greater thickness than the side thereof shown at the left. In this connection, it should be noted that the canted arrangement as shown in Fig. 2 is preferred when the harness jacket is one which is converted from an existing metallic tie plate of the canted type whereas the canted arrangement of Fig. 2a is preferred when the harness jacket is one which is converted from an existing metallic tie plate of the non-canted type.

Thus, in accordance with my invention, the rails may be canted inwardly in any suitable manner, for example, as described above. The cant causes the rails to take primary positions which resist side sway with the attendant advantages.

In accordance with a preferred form of the invention, the hereinbefore described shoe S is formed in part from a plurality of built-up layers of material which contribute in an important sense to improved operating efficiency. Thus, as shown in Fig. 3, it is desirable for the sole plate b of said shoe S to comprise a lower layer m having a thickness approximately of $\frac{1}{64}$ " and constructed from very high modulus vulcanized rubber. Directly above this layer m, there is a tightly woven fabric sheet m1, or equivalent, having a thickness of $\frac{3}{32}$ " approximately. Overlying the sheet m1, there are two or more spaced open-weave friction fabric sheets m2 having a thickness of approximately $\frac{1}{32}$ ".

Preferably, the cushion section b1 comprises an upper layer n of very high modulus vulcanized rubber having a thickness of approximately $\frac{1}{64}$ ". Directly below the rubber layer n, there is disposed a tightly woven friction fabric sheet n1 having a thickness of approximately $\frac{3}{32}$ ". Below the sheet n1, there is disposed two or more open-weave friction fabric sheets n2 having a thickness of approximately $\frac{1}{32}$ ". Beneath the fabric sheets n2, there is disposed a plurality of rubber layers n3, n4, n5, each having a thickness of approximately $\frac{1}{16}$ " and these rubber layers being formed, respectively, from very high modulus vulcanized rubber, high modulus vulcanized rubber, and medium modulus vulcanized rubber, for example. Between the rubber layer n5 and the upper fabric layer n2, the shoe S is formed, preferably, from a mass r of low modulus vulcanized rubber.

A built-up construction of the character described above is used so that the rubber shoe S as a whole may have the correct cushioning or deflecting qualities. As clearly appears, the built-up arrangement is of such character that it is adapted to withstand shock or impact at the upper and lower surfaces while remaining highly resilient to a desired degree through the major interior area thereof.

In accordance with an important feature of the invention, it is desirable that preferably all of the fabric layers m1, m2 and n2 terminate interiorly of the outer boundaries of the shoe S, Figs. 3, 3a. Further, as shown in said Figs. 3, 3a, it is desirable that the fabric layers m1, m2 terminate short of the vertical surfaces defining the passages b2. In this manner, said fabric layers are effectively sealed by the rubber and hence are incapable of serving wick-fashion to conduct moisture or other agents or damaging substances interiorly of the rubber structure. In this fashion, the life of said rubber structure is increased greatly compared to an arrangement wherein such wick action exists.

Referring particularly to Figs. 1 and 5, the herein described passage a2 of the harness jacket H is shown as of generally square or rectangular configuration and the corners of said passage are rounded or curved as shown. Further as illustrated on the drawings, the corners of the cushion section b1 are rounded or curved in correspondence with the configuration at the corners of said passage a2. This is advantageous because eliminating any tendency of the cushion section to wedge in a corner of the harness jacket. If such wedging should occur, normal deflection would be obstructed and there would be a possibility that the rubber material might be torn under the weight of traffic.

It shall be understood that the herein described

graduated deflection groove b5, the built-up construction described above and illustrated in Fig. 3 and the centering arrangement for the cushion section are not to be limited to use with the lock

5 clip tie plate arrangement of this application. As well, for example, the features referred to immediately above may be embodied in other rubber tie plate arrangements such, for example, as described in my aforesaid U. S. Letters Patent No. 2,110,894 and otherwise as will be understood.

10 In Fig. 6, I have illustrated my invention as having application to a concrete supporting structure 10 which is utilized in lieu of the cross tie arrangement of Figs. 1 and 2. Cast 15 interiorly of the supporting structure 10 is a nut member 11 which is disposed below a plate 12, access to said nut member 11 being had by way of the sleeve 13. A bolt 14 passes downwardly through the aligned passages of the lock 20 clip, the harness jacket and the sole plate, said bolt 14 being threaded into the nut member 11 so as to retain the parts in assembled relation.

While the invention has been described with respect to certain particular preferred examples 25 which give satisfactory results, it will be understood by those skilled in the art after understanding the invention, that various changes and modifications may be made without departing from the spirit and scope of the invention and it 30 is intended therefore in the appended claims to cover all such changes and modifications.

What is claimed as new and desired to be secured by Letters Patent is:

1. A tie plate arrangement comprising a 35 cushion section of rubber-like material adapted to form a seat for the base of a railroad rail, and a deflection groove extending downwardly into said cushion section and being adapted to be disposed transversely of said rail, said groove 40 having maximum depth at the inside of said rail and the groove depth gradually decreasing toward the outside of said rail.

2. A tie plate arrangement comprising a cushion section adapted to form a seat for the 45 base of a railroad rail, the upper portion of said cushion section, in descending relation, comprising an upper layer of high modulus rubber, a friction fabric sheet, and one or more layers of lower modulus rubber, the lower portion of said 50 cushion section, in ascending relation, comprising a lower layer of high modulus rubber and one or more friction fabric sheets, said cushion section, throughout the intermediate portion thereof, being formed from low modulus rubber.

3. In a tie plate arrangement for a railroad rail, a metallic harness jacket having an interior wall surface defining a passage extending vertically therethrough, a resilient cushion section disposed in said passage so as to form a seat for 55 the rail, the cross-sectional area of said cushion section being less than the cross-sectional area of said passage, and means coacting with said wall surface of the harness jacket for centering the cushion section in said passage, said means

60 comprising a projecting section of said cushion section which extends into engagement with at least a part of the wall surface of each side of the harness-jacket, the area of said projecting section being small compared with the area of the vertical sides of said cushion section whereby substantially the entire area of said vertical sides of the cushion section are spaced from the 65 adjacent vertical sides of the harness jacket.
